UNITED STATES PATENT OFFICE.

CHARLES A. NELSON, OF UTICA, NEW YORK, ASSIGNOR TO SAVAGE ARMS CORPORATION, OF UTICA, NEW YORK, A CORPORATION OF NEW YORK.

FIREARM.

1,293,877.

Specification of Letters Patent. Patented Feb. 11, 1919.

Application filed July 17, 1917. Serial No. 181,066.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

In magazine guns of the class wherein the magazine feed is in a direction transverse of the barrel's axis, as vertically or substantially so, it is frequently desirable that the cartridges be fed in one by one by hand. This invention therefore consists in a novel adapter or "dummy magazine" whereby a gun of the class indicated and provided with a cavity to which a magazine might be fitted and with an opening for the ejection of the spent shells may be used as a single-loader, the adapter or dummy magazine being so constructed as to favor the convenient and quick-hand-introduction of the cartridges into the gun, to insure their being held in the gun in proper position for advancement by the bolt into the breech-chamber without obstruction or undue mutilation thereof, and to permit their withdrawal from the breech-chamber and ejection without jamming. The invention contemplates particularly magazine guns adapted for the use of rim cartridges, and since in such guns the underneath face of the breech-bolt is more or less below the lowest horizontal plane of the breech-chamber, I form the dummy magazine or adapter in order to support the cartridge for advancement into the breech-chamber without obstruction so that the cartridge stands with its bullet end or nose up-tilted in more or less exact registry with the mouth of said chamber and the rear end of the cartridge-supporting seat of the dummy magazine or adapter enough below the breech-bolt to permit the latter to act without obstruction, the seat-portion of said dummy magazine being spring-upheld and adapted to yield downward out of the way of the breech-bolt when the latter is moved forward. Said seat is further channeled or recessed in the longitudinal direction so as to resist the rolling-out of the cartridge after it has been introduced and before breeching; and at its forward portion and on the inside it has a lateral wing or upstanding cheek or side support to keep the bullet-end of the cartridge true (against lateral displacement) to the mouth of the breech-chamber until the

breeching operation has advanced the cartridge more or less into said chamber.

The accompanying drawings fully illustrate my invention,

Figure 1 showing the breech part of a gun of the type indicated in longitudinal section, with the adapter or dummy magazine in place and a cartridge in position for breeching;

Fig. 2 is a similar view on a larger scale, the cartridge being shown partly breeched;

Fig. 3 is a sectional view on line 3-3 of Fig. 2;

Fig. 4 is a side elevation of the adapter as a whole, and Figs. 5 and 6 are plan views of the upper or movable member and lower or base member, respectively, of the same;

Fig. 7 is a vertical longitudinal sectional view of the adapter;

Fig. 8 a transverse sectional view thereof on line 7-7, Fig. 4, with the spring removed; and

Fig. 9 is a plan view of the attaching plate of the base member.

The gun shown by way of illustration is similar to that set forth in my Patent No. 1,168,026. *a* is the barrel extended rearwardly to form the breech-casing *b*; *c* the breech-chamber; *d* the space immediately back of the same in which the cartridge is held in position for advancement into said chamber and into which the spent shell is withdrawn on ejecting; *f* the vertical opening adapted to receive the magazine box and in the present instance containing the improved dummy magazine, the same being formed in the stock *g* and breech casing *b* and leading to the space *d*; *h* (Fig. 3) the ejecting opening, formed laterally in the breech-casing and also leading to said space *d*, the same in the present case being also employed for introducing the cartridges one by one by hand; *i*' and *i*'' the rear or non-rotary and the forward or rotary members, respectively, of the breech-bolt, the former having an operating handle movable in the slot *j* and the latter a depending rib *k* adapted to engage the upwardly spring-pressed platform of the magazine box (when present) and be blocked thereby against forward movement when the last cartridge has been fired, said breech-bolt extending below the lowest horizontal plane of the breech-chamber *c*; *l* the extractor on the forward end of the breech-bolt; and *m* the ejector co-operative with the

extractor in the well-known way to eject the spent shell through opening *h*.

The dummy magazine may conveniently be made of sheet material and constructed as follows: There are two members, one telescoped into the other, and a spring to hold the upper or movable member normally elevated relatively to the lower or base member.

The base member has a basal or attaching part *n* consisting of a flattened tube having an opening *o* cut in one wall thereof from one end thereof toward but not to the other end thereof, the opening *o* being somewhat narrower than the part *n* and thus leaving inwardly facing grooves *p* at both sides thereof. An upstanding tubular shell *q*, shaped in cross section the same as said opening, is fitted thereto at its lower end and has lateral outwardly turned flanges *r* which are received in the grooves *p*, the material forming the grooves being compressed so that the flanges are permanently gripped and held by the basal part *n*. Near the top of shell *q* each side wall thereof has a part *s* cut out and bent inward to form a stop.

The upper or movable member is also a shell, *t*, of the same cross-sectional shape as and adapted to fit snugly, but so as to move freely up and down in the shell *q*, its side walls having openings *u* which receive the stops *s* and said wall thereby coacting therewith to limit the upward movement of the movable member. The shell *t* is closed at the top, to wit, by a wall *v* which is thus preferably arranged and formed: Said wall slopes upward from left to right in the drawings and it is channeled longitudinally, its inner side being elevated at all points above its outer side and gradually rising toward the right to a point near the right-hand end of said wall, where it slopes suddenly downward. At the point *v''* of greatest eminence wall *v* forms a cheek or side support or abutment for the bullet or nose end of the cartridge.

The spring, *w*, may be any suitable form of spiral spring; it is housed in the shells *q* and *t* and interposed, more or less compressed, between the wall *v* and the part *n* of the base member.

I do not wish to be limited to the movability of the upper or movable member being rectilinear, as in the telescopic arrangement herein described by way of illustration.

The dummy magazine as thus constructed is fitted into the opening *f* of the gun as shown in Figs. 1 and 2, being therein held by a screw *x* passed through a hole *y* in the forwardly projecting portion *z* of the basal part *n* of the base member. When thus positioned the slope of wall *v*, which forms the cartridge seat, is such that at its forward end its top surface or seat is about flush with the bottom or lowest horizontal plane of the

chamber *c* while at its rear end said seat is below and adapted to be overridden by the breech-bolt when the same is advanced (see Figs. 2 and 3), the movable member of the dummy magazine being held to maintain said wall in this position by the counter-influences of the stops *s* and spring *w*.

The outer side of wall *v* is low enough to permit the cartridge to be introduced readily by hand, but it nevertheless serves to retain the cartridge when once entered, at least unless the gun is canted considerably to the right (the ejecting opening *h* being in the present instance, as usual, on the right side of the gun). The inner side *v'* of wall *v* coacts with the outer side thereof to prevent lateral rolling of the entered cartridge, its eminence or side stop *v''* keeping the nose of the cartridge in true registry with the chamber *c*, i. e., against inward lateral movement and consequent mutilation when the cartridge is advanced into said chamber. The described slope of wall *v*, while bringing the nose vertically in registry with the chamber *c* permits the breech-bolt when advanced to ride up on and cam down the upper or movable member of the dummy magazine so that the bolt may accomplish its complete forward or breeching movement. When the shell is extracted after firing the slope at the right of the eminence *v''* in Fig. 7 allows the rim of the cartridge to move back without interference. The slope downward from said eminence to the left obviously leaves the ejector fully exposed so as to properly function with the extractor, when the shell is ready to be ejected.

Having thus fully described my invention, what I claim as new and desire to secure by Letters Patent is:—

1. In a gun, the combination, with the breech-including part thereof having a breech-chamber, a cartridge-receiving space back of and adjoining the breech-chamber and an opening extending upwardly to said space, and with a breech-bolt, of means in said opening for supporting a cartridge ahead of the retracted bolt including a spring-upheld downwardly compressible cartridge-supporting member confined to rectilinear up and down movement and having at its top a forwardly and upwardly inclined breech-bolt camming-down surface lower at the rear than and adapted to be overridden and cammed down by the advancing breech-bolt and forming a cartridge seat.

2. In a gun, the combination, with the breech-including part thereof having a breech-chamber, a cartridge-receiving space back of and adjoining the breech-chamber and an opening extending upwardly to said space, and with a breech-bolt, of means in said opening for supporting a cartridge ahead of the retracted bolt including telescoped members, one being a spring-upheld

cartridge-supporting member downwardly 5
depressible in the other and having at its
top a forwardly and upwardly inclined
breech-bolt camming-down surface lower at
the rear than, and adapted to be overridden
by, the advancing breech-bolt and forming a
cartridge-seat.

3. In a gun, the combination, with the
breech-including part thereof having a
10 breech-chamber, a cartridge-receiving space
back of and adjoining the breech-chamber,
and an opening extending upwardly to said
space and also a lateral opening leading to
said space, and with a breech-bolt extending
15 below the lowest horizontal plane of the
breech-chamber, means fitted in the first

opening for supporting a cartridge ahead of
the retracted bolt, said means having a
spring-upheld downwardly depressible car-
tridge-supporting seat formed with its for- 20
ward portion elevated to about the level of
said plane, whereby to support the cartridge
with its nose in registry with the breech-
chamber, and with its rear portion below and
adapted to be overridden by the advancing 25
breech-bolt, said means having opposite said
lateral opening and at the relatively inner
side of the forward part of said seat an up-
standing side-support for the cartridge.

In testimony whereof I affix my signature. 30

CHARLES A. NELSON.
